UNITED STATES PATENT OFFICE.

MARY P. OFFUTT, (NOW BY MARRIAGE MARY P. CLEAVER,) OF NEW YORK, N. Y.

PAPER DOLL.

1,330,043:

Specification of Letters Patent.

Patented Feb. 3, 1920.

Application filed January 31, 1917, Serial No. 145,574. Renewed December 4, 1919. Serial No. 342,478.

To all whom it may concern:

Be it known that I, MARY P. OFFUTT, a citizen of the United States, residing at New York, county and State of New York, 5 have invented certain new and useful Improvements in Paper Dolls, of which the following is a specification.

This invention relates to improvements in paper dolls, and has for its general object 10 to provide for increasing the amusing properties of devices of that kind and additionally to provide for instructing the user in the prevailing mode or style and construction of articles of wearing apparel; and in 15 the practice of properly arranging these on the body of the doll. And to this end the invention resides in doll wearing apparel made of paper and constructed on the same general principle as ordinary apparel made 20 of fabric; and in a paper doll adapted for accommodating the aforesaid apparel.

Other objects will appear and be better understood from that embodiment of my invention of which the following is a specification, reference being had to the accompanying drawings forming part hereof, in which:

Figure 1, is a front elevation of the doll body as the same appears when cut from a 30 sheet of card board and colored or printed on a sheet of paper so as to be cut therefrom.

Fig. 2, is a plain view of the petticoat as the same will appear when stamped out of a sheet of paper, or as it may appear when 35 printed on a sheet of paper in connection with the doll body.

Fig. 3, is a view similar to Fig. 2 of the dress.

Fig. 4, is a view similar to Fig. 2 of the 40 coat.

Fig. 5, is a view similar to Fig. 2 of the hat.

Fig. 6, is a view similar to Fig. 2 of one 45 of the socks.

Fig. 7 is a view similar to Fig. 2 of one of the bootees.

Fig. 8, is a view similar to Fig. 2 of the 50 drawers.

Fig. 9, is a detail perspective of the dress 55 assembled and ready to be applied to the doll body.

Fig. 10, is a view similar to Fig. 9 of one of the socks.

Fig. 11, is a view similar to Fig. 9 of one of the bootees.

55

Fig. 12, is a front elevation of the doll when dressed.

The device of this invention may be provided in the form of a single sheet of paper 60 having printed thereon the design of a nude doll and also designs representative of the various articles of apparel necessary to completely clothe the doll. The grouping of these several designs as shown in Figs. 1-8 being such as to permit of removing each 65 from the sheet by cutting the same with a knife or scissors along the outline thereof. Or the device may be provided with the doll body separate and distinct from the sheet on which the designs illustrating the articles of 70 wearing apparel are printed; in which event the doll body may be formed of paper-board or of stock heavier than that of the paper sheet, it being desirable in some instances to have the paper material of the apparel more 75 flexible than that forming the doll body. Or the device may take the form of a nude doll formed of paper-board and separate pieces of apparel cut or stamped on sheets of relatively thin paper, in which event a 80 container will be provided for the doll body and the various pieces of apparel.

It is proposed to have the design of the doll so colored and composed as to be representative of a nude infant standing upright; 85 and the various articles of apparel will be suitably colored to correspond to the colors of the articles of clothing which they represent.

In Fig. 1 the doll body 5 is accurately cut 90 from paper-board, the hair and facial features being printed in multi-color on the head 6. The arms 7-7 extend obliquely outward and downward and from the trunk 8 and the legs 9-9 are slightly spread apart 95 as shown. The rear (not shown) of the doll body 5 is suitably colored or printed so as to represent the rear of a nude infant. The drawers 10 consist of a single sheet of paper folded at its middle to provide corresponding portions 11 and 12 the free end of one of which has a tab 13 folded inwardly and pasted to the inner surface of the corresponding end of the other portion. The drawers so constructed pass upwardly over 100 the legs of the doll and the intermediate

portion of the drawers is such as to nicely fit around the hips of the doll while the waist portion is made relatively small so as to fit the waist by cutting a V 14 into one side of the upper end portion of the drawers and inwardly sloping the portion directly opposite.

The petticoat 15 has a front portion 16 in the upper end of which is a recess 17 to 10 adapt the portion 16 to extend around the neck and over the shoulders of the doll and tabs 18 are provided which are pasted to the upper ends of the back sections 19 and 20 of the petticoat. The upper edges of the 15 back sections are curved so as to coöperate when joined together to provide a continuation of the recess 17. The accordion plaits 21 which connect the lower portions of the adjacent sides of the sections 16, 19 and 20 20 operate to expand or fluff the lower portion of the petticoat when the same is arranged on the body of the doll as shown. It will be noted that elongated openings appear in the opposite sides of the petticoat above the 25 plaits. The provision of these openings facilitates the operation of adjusting the petticoat onto the body of the said doll by providing spaces through which the arms of the doll may readily pass. In the operation 30 of arranging the petticoat on the doll body 5 and in removing the petticoat therefrom the plaits 21 permit of expanding the lower ends of the openings sufficient to clear the hands or the lower ends of the arms 7-7. 35 A dove tail tongue 22 on one of the back sections is arranged so as to be adjusted into a correspondingly shaped recess 23 in the edge of the other section whereby to lock or fasten the petticoat to the body of the doll. 40 The flexibility of the paper of which the petticoat is formed is such as will permit of readily disengaging the tongue from the recess without danger of tearing the sections when it is desired to remove the petticoat.

45 The dress 24 comprises a front portion 25 the upper end of which is joined by tabs 26 to the back portions 27 and 28. The upper edges of the sections 25, 27 and 28 are constructed so as to coöperate to provide an opening 29 for the neck of the doll. The said sections also coöperate to provide short sleeves 30 the outer sides of which from the shoulders to the lower ends are open. Plaits 31 similar to the plaits 21 connect the lower 50 ends of the sections 25, 27 and 28. The opposite sides of the dress from the upper ends of the plaits to the lower ends of the sleeves are open so as to facilitate the operation of adjusting the dress onto the body of the doll 55 by providing openings sufficiently large to permit the arms 7-7 to pass therethrough when the dress is put on in the manner previously described in connection with the petticoat 15. The dress, too, in the back portions 27 and 28 thereof is provided with a

dove tail tongue 32 and a dove tail recess 33 to receive the tongue whereby the dress may be secured to the body of the doll in the same manner as described in connection with the petticoat.

The socks 34 are formed by folding a relatively narrow oblong strip of paper at its middle so as to provide front and back portions 35 and 36 and providing one of these portions with tabs 37 which are pasted to the inner face of the other portion. In this way flat pocket shaped structures are provided which may be readily slipped over the doll's feet. The bootees 38 are constructed the same as the socks 34 except that they are shorter and wider than the socks so as to be readily slipped over the socks and cover the portion of these which extend over the feet and ankles of the doll.

The coat 39 may be constructed so as to correspond with the petticoat or the dress; or as shown the front of the coat may be made up of the two sections 40 and 41 the upper ends of which are connected to the upper end of the back sections 42 by tabs 43, 90 the sections 41 and 42 being provided with the dove tail tongue and recess structures 44 which operate to connect the coat to the body of the doll. In connection with the coat it will be observed that the plaits mentioned in connection with the petticoat and the dress may be eliminated so as to leave the opposite recesses in the sides of the coat, and which open through the lower edge thereof, the sleeves 45 being closed at their outer sides as shown. It will be understood that all or any of the modifications shown in connection with the structure of the coat may be incorporated with the petticoat and dress.

The bonnet 46 consists of a solid half round portion 47 which provides the back and an arcuate shaped front portion 48 which is joined by a crease hinge 49 and by tabs 50 to the back 47. The bonnet is so constructed and adapted as to be placed onto the doll's head so that the face of the doll will appear in the opening afforded by the shape of the front 48.

From the foregoing it will be noted that each article of apparel is so constructed that it may readily be applied and detached from the doll; and further that each piece requires practically the same degree of care in selecting and adjusting it to its proper position that is required in selecting and adjusting ordinary doll clothing onto a doll. It will be understood that the style or mode of the articles may be varied at will so as to be representative of the popular fashion. It will be further observed that the device is comparatively simple and inexpensive to manufacture and that many changes other than those indicated may be made therein without departing from the spirit of the

invention as pointed out in the appended claim.

What is claimed as new is:

5 A paper doll comprising a doll body formed of a sheet of card board or the like and apparel therefor formed of paper and consisting of front and back sections arranged over the front and back of the body of the doll, certain of said sections being

provided with interfitting parts interlocked one within the other and tabs arranged on the other sections for detachably connecting the same to the first mentioned sections.

In testimony whereof I have signed my name to this specification this 17th day of January, 1917.

MARY P. OFFUTT.
